US0D1032952S

(12) **United States Design Patent** (10) Patent No.: **US D1,032,952 S**
(45) Date of Patent: ** Jun. 25, 2024

(54) **WELDERS MASK**

(71) Applicant: **Sundström Safety Aktiebolag**, Lagan (SE)

(72) Inventor: **Peter Weidmert**, Lagan (SE)

(**) Term: **15 Years**

(21) Appl. No.: **35/516,179**

(22) Filed: **Mar. 16, 2022**

(80) **Hague Agreement Data**

Int. Filing Date: **Mar. 16, 2022**

Int. Reg. No.: **DM/220309**

Int. Reg. Date: **Mar. 16, 2022**

Int. Reg. Pub. Date: **May 6, 2022**

CLAIM

The ornamental design for a welders mask, as shown and described.

DESCRIPTION

1. Welders mask

FIG. 1.1: is a front left perspective view;

FIG. 1.2: is a front view;

FIG. 1.3: is a top view;

FIG. 1.4: is a left side view;

FIG. 1.5: is a right side view;

FIG. 1.6: is a rear view; and

FIG. 1.7: is a bottom view.

The equal-length broken lines in the reproductions depict portions of the welders mask that form no part of the claimed design.

1 Claim, 7 Drawing Sheets
